COVERED HAMMOCK AND SUPPORT THEREFOR

Anton Riedel, Zugspitzstrasse 64, Gauting, near
Munich, Germany

Filed Dec. 10, 1964, Ser. No. 82,978

Claims priority, application Germany July 3, 1964

Term of patent 14 years

(Cl. D5—1)

FIG. 1

FIG. 2

FIG. 3

FIG. 4

FIGURE 1 is a perspective view of the covered hammock and support therefor embodying my new design with the covers in closed position;

FIGURE 3 is a perspective view thereof with one cover in elevated position and the other in a downwardly inclined position;

I claim:

The ornamental design for a covered hammock and support therefor, as shown.
